UNITED STATES PATENT OFFICE.

ADAM ZISKA, JR., OF MILWAUKEE, WISCONSIN, ASSIGNOR TO C. F. BURGESS LABORATORIES, A CORPORATION OF WISCONSIN.

ROCK SEPARATOR.

Application filed September 27, 1922. Serial No. 590,949.

To all whom it may concern:

Be it known that I, ADAM ZISKA, Jr., a citizen of the United States, residing at Milwaukee, in the county of Milwaukee, State 5 of Wisconsin, have invented certain new and useful Improvements in Rock Separators; and I do hereby declare the following to be a full, clear, and exact description of the invention, such as will enable others 10 skilled in the art to which it appertains to make and use the same.

This invention relates to a method and apparatus for treating wood chips or similar materials, for the purpose of separating 15 therefrom foreign particles such as rocks, nails, bits of iron and other hard objects substantially heavier than the chips.

This invention may be understood by considering its use as applied to the treatment 20 of wood chips. In making products, such as wallboard, out of waste wood from saw mills or other wood working plants, it is necessary to separate all hard foreign objects from the wood chips, due to the fact that if these 25 pieces of hard material get into the machinery they cause breakage. Various attempts have been made to separate the pieces of foreign material from the chips, and this constitutes one of the most expensive steps 30 in the utilization of the wood material. Even when extraordinary precautions are taken it has been almost impossible to remove all of the pieces of foreign material.

As suggested above, the present invention 35 is directed to the provision of a simple and effective method and apparatus for treating materials, such as wood chips, whereby all hard foreign substances may be completely separated from the material under treatment. The improved method, as applied to 40 the treatment of wood chips, comprises passing the chips through a body of liquid, preferably water. These chips consist of edgings, trimmings and other saw mill refuse 45 all of which has preferably been converted into hog chips at the saw mill. The water into which the chips are deposited or dropped is caused to flow in such a direction that it tends to buoy up the chips. This is necessary in the treatment of ordinary saw mill 50 refuse due to the fact that a large portion of the chips (as much as 50% in some instances) consists of water-soaked chips, so that if they were deposited in a receptacle containing quiescent water, they would sink

to the bottom, together with the foreign particles. This condition of the chips renders it impossible to separate the foreign particles by attempting to float the chips on the surface of a quiescent body of water. This invention is particularly adapted to treat material of this nature, for provision is made whereby the separating liquid is caused to flow in such a direction and with such a velocity that it buoys up all the wood chips 60 while permitting the solid foreign objects to settle.

In carrying out my improved process, I prefer to deposit the chips in a receptacle in any suitable manner, as by dropping them 70 into the receptacle. Water is introduced into the bottom of the receptacle which is arranged so that the water flows in an upward direction, thus tending to buoy up the chips. I preferably employ a means where- 75 by the velocity of the water may be regulated to the desired value depending upon the nature of the material being treated. The velocity should be high enough to buoy up all the particles which are to be utilized, 80 while at the same time, permitting the foreign particles to settle to the bottom of the receptacle.

The chips which have been dropped into the receptacle have a tendency to lodge near 85 the surface of the water in a substantially semi-solid mass. When this occurs, experience has shown that some of the foreign particles are supported by the mass of chips and therefore prevented from settling to the 90 bottom of the receptacle. It is, therefore, advisable to provide a means whereby all of the chips may be forced under the surface of the liquid, and this is preferably done in such a manner that the chips are agitated 95 considerably, whereby the semi-solid forma- 100 tion is broken up and the hard heavy par- ticles are free to settle to the bottom. This forcing of the particles under the surface of the water should be done by means of a suitable agitating device arranged so that it pokes the chips under the surface of water and preferably under the lower edge of a 105 dam. If the process is carried out in this manner the chips rise to the surface of the liquid beyond the dam and may be dis- 110 charged from the receiving vessel at this point. The chips may then be deposited on a suitable conveyor of such a character that the water drains through the conveyor and

the chips are delivered at the other end thereof practically free from drops of water.

If it is so desired a further step may be included in the improved process. The 5 chips may be sprayed subsequent to their discharge from the treating receptacle. Means for spraying the chips may be provided over the conveyor above referred to. This additional step may be used for the purpose of 10 removing from the chips particles of sand, and other minute particles of hard foreign material.

The improved process and apparatus which constitute the subject matter of this 15 invention may be understood more fully from the following detailed description which is to be considered in conjunction with the accompanying drawings in which

Fig. 1 is a transverse section of a wood 20 chip treating plant showing one form of the improved apparatus;

Fig. 2 is a plan view of the separating tank or receptacle, and the agitating device associated therewith, and,

Fig. 3 is a vertical section taken on line 3—3 of Fig. 2 showing the details of construction of the separating tank and the agitator.

For the purpose of illustration, the apparatus shown in the accompanying drawings 30 shows the application of the improved method and apparatus to the treatment of wood chips.

By referring to Fig. 1 it may be noted that 35 the saw mill refuse, which has been converted into hog chips, is blown or otherwise forced through the pipe 1 into a suitable cyclone 2. From the cyclone 2 the chips fall through a suitable chute 3 into the separating receptacle or tank 4. It may be noted that the upper portion of the tank 4 is divided into two compartments by a partition 5, and that the chips drop from the chute 3 into one of these compartments. Water or other suitable liquid may 40 be supplied to the bottom of the tank 4 through the pipes 6, the water being supplied in a manner to be described hereinafter. A vent or opening 7 is provided in one side of the tank 4 at a point opposite to the compartment in which the chips are deposited. This opening 7 is preferably made in such a manner that the lower edge thereof is slightly above the lower edge of the dam 45 or partition 5. Accordingly, the water which flows in through the pipes 6 passes upward through the tank 4 and discharges through the opening 7. The chips 8 which have been dropped through the chute 3 strike the surface of the water and are then subjected to the action of a suitable agitating device to be described in detail hereinafter. The reciprocating rods 9 of the agitating device 10 force the chips down into the water 50 and stir them up to such an extent that any

solid particles of foreign material are free to settle to the bottom of the tank 4. The agitating device 10 is preferably so arranged that the reciprocating rods 9 force the chips under the lower edge of the dam 5. The 70 flowing water, which has a tendency to buoy up the chips, causes the chips to rise on the other side of the dam 5 until they come to the surface of the liquid. As the water discharges through the opening 7 the washed 75 chips are carried through with it and deposited on a suitable conveyor 11. This conveyor, which is preferably inclined at an angle to the horizontal, is provided with a plurality of openings therein through which 80 the water on the chips may drain into a suitable drip pan or chute 12. If it is so desired, a suitable pipe 13 having a spray attached to the lower end thereof may be mounted near the conveyor in such a manner 85 that the water issuing from the spray washes the chips a second time for the purpose of removing all particles of sand and other finely divided hard particles. As shown in the drawings, the conveyor 11 carries the chips to an attrition mill 14.

The separating tank, mentioned above, comprises a water-tight receptacle of ordinary construction (see Fig. 3). The upper portion of this tank is divided into two compartments by the partition 5, and the lower part is divided into four compartments by suitable partitions 15 and 16 which join at the center of the tank. The purpose of the partitions 15 and 16 is to provide a means 100 for preventing eddy currents in the bottom of the tank which might be produced by uneven flow through the pipes 6. With the tank constructed as shown, the water in each compartment flows in a substantially 105 vertical direction without producing any swirls or downward currents tending to carry the chips to the bottom of the tank.

If it is so desired, suitable hand holes 17 may be provided near the bottom of the tank 110 for the purpose of affording easy access thereto to remove the foreign particles separated from the chips and which have settled in the bottom of the tank.

The agitating device comprises a plurality 115 of rods 9 slidably mounted on a suitable support 18. These rods are arranged so that they pass through the side of the tank 4, and are of such a length that when they are reciprocated they are adapted to force the 120 chips under the surface of the water and under the lower edge of the dam 5. Each of the rods 9 is provided near the upper end thereof with rack teeth 19 which are adapted to be engaged by a suitable toothed sector 125 20. The sector 20 is pivoted on a suitable support, for example, the shaft 21 which may be journaled on the side of the tank 4. A cam shaft 22 having a plurality of cams 130 23 mounted thereon is provided, this shaft

being arranged in close proximity to the sectors 20 whereby the cams may actuate the sectors for the purpose of reciprocating the rods 9. The sectors 20 may be held in contact with the cams 23 by means of tension springs 24 or other suitable means. The cams may be timed so that the rods 9 reciprocate in any desired manner. For example, if six rods are used as shown in the drawings, the cams may be spaced 30° apart so that the rods reach their extreme positions at different times.

The cam shaft 22 may be driven by any suitable means, such as the belt 25 (see Fig. 1) which is driven by a main drive shaft 26. The conveyor 11 and the attrition mill 14 may also be driven by the drive shaft 26 by means of suitable belts or chains 27.

The water circulating system comprises a suitable storage tank 28 which is preferably located at a point below the level of the bottom of the separating tank 4, for example, below the floor 29 of the treating plant. Water may be supplied to this tank through the pipe 30 which is provided with a suitable valve 31. Water may be pumped from the tank through a suitable filter 32 by means of a pump 33. As shown in the drawings, a priming pipe 34 may be provided for priming the pump 33, and a drain pipe 36 for draining the tank 28 and the pump 33, the passage of water into the drain pipe being controlled by suitable valves 35 and 37. The water which is pumped from the tank 28 passes through a suitable control valve 38 into the bottom of the tank 4 through the pipes 6. The water which passes out of the tank 4 over the spillway 39, and the water which drains from the chips on the conveyor is returned to the tank 28 by the pan or chute 12.

From the above description it should be apparent that the improved process comprises a means whereby wood chips or other similar material may be treated in such a manner that all hard foreign particles of a substantially higher specific gravity than the material under treatment may be completely separated therefrom. Generally speaking, this improved process consists in passing the material to be treated through a body of liquid, the liquid being caused to flow in such a direction and with such a velocity that the material under treatment is buoyed up while the foreign particles are permitted to settle. This process may be carried out by means of the apparatus hereinbefore described. The water is introduced into the tank 4 in such a manner that it flows in an upward direction, thereby buoying up the chips which are being treated. The velocity of the water may be positively controlled by means of the control valve 38, and an efficient agitating device is provided for thoroughly agitating the chips and

forcing them under the surface of the water in such a manner that the foreign particles are free to settle to the bottom of the receptacle.

It is to be distinctly understood that while this invention has been described as applied to the treatment of wood chips, yet it is equally applicable to the treatment of any divided material by means of liquid, especially when the substance to be treated is of the same or substantially the same specific gravity as the liquid used. The improved process is applicable in any case in which it is necessary to maintain or support particles near the surface of a liquid, the particles being of such a specific gravity that part of them, at least, would settle in a quiescent body of the liquid.

Furthermore, it is to be understood that the present invention is not limited to the particular embodiments shown and described, for the size, proportions and arrangement of the various parts may be modified without departing from the scope of the invention as defined in the appended claims.

I claim:

1. The process of treating material of the type described for the purpose of separating therefrom foreign objects of a higher specific gravity than the material, which consists in depositing the material in a receptacle in which a liquid is flowing in an upward direction with such a velocity that the material is buoyed up thereby, agitating the material and forcing all of it under the surface of the liquid, continuously discharging the material from the receptacle, and spraying the discharged material.

2. The process of treating material of the type described for the purpose of separating therefrom foreign objects of a higher specific gravity than the material, which consists in depositing the material in a receptacle in which a liquid is flowing in an upward direction with such a velocity that the material is buoyed up thereby, agitating the material and forcing all of it under the surface of the liquid, continuously discharging the liquid together with the material, and spraying the material discharged from the receptacle.

3. The process of treating wood chips, part of which are water soaked, for the purpose of separating therefrom foreign objects of higher specific gravity than the chips, which consists in dropping the chips into a receptacle containing water flowing upward through a plurality of inlet pipes in the bottom of the receptacle and out through a discharge port near the top thereof, and simultaneously agitating the chips and forcing them under a partition in the receptacle, the velocity of the water being sufficient to carry substantially all of the chips out through the discharge port.

4. In an apparatus of the type described, a receptacle, means for causing a liquid to flow in an upward direction in said receptacle, means for depositing material of the type described in said receptacle, means for continuously agitating said material and forcing it under the surface of said liquid, said receptacle having a discharge port near the top thereof through which said material and liquid may be continuously discharged. 35
5. An apparatus for treating wood chips, part of which are water soaked for the purpose of separating therefrom foreign objects of a higher specific gravity than the chips, comprising a receptacle, means for dropping chips into said receptacle, means for supplying water to the bottom of the receptacle and discharging the water through a port near the top of the receptacle, a partition within 40
- 10 said receptacle extending substantially below the edge of the surface of the liquid, an agitating device arranged so that it forces all of the chips under the surface of the water and under the lower edge of said partition while agitating the chips, and means 45 for controlling the supply of water to said receptacle so that the velocity of the water is high enough to carry substantially all of the chips through the discharge port, while 50 permitting the foreign objects to settle to the bottom. 55
6. In an apparatus of the type described, a receptacle, and an agitating device comprising a plurality of rods, a guide bearing 60
- for each rod, and means for reciprocating said rods in said bearings said agitating device being arranged so as to force material on the surface of a liquid in the receptacle under the surface of the liquid and under a partition in said receptacle. 65
7. In an apparatus of the type described, a receptacle, and an agitating device comprising a plurality of rods each having rack teeth near one end thereof, a guide bearing for each rod, a toothed sector adapted to engage each of said rods, and means for actuating said sectors to reciprocate said rods said agitating device being arranged so as to force material on the surface of a liquid in the receptacle under the surface of the liquid and under a partition in said receptacle. 70
8. In an apparatus of the type described, a receptacle, and an agitating device comprising a plurality of rods each having rack teeth near one end thereof, a guide bearing for each rod, a toothed sector adapted to engage each of said rods, a shaft supporting said sectors and a second shaft carrying a plurality of cams for actuating said sectors to reciprocate said rods said agitating device being arranged so as to force material on the surface of a liquid in the receptacle under the surface of the liquid and under a partition in said receptacle. 75

In testimony whereof I affix my signature.

ADAM ZISKA, JR.
